PENNSYLVANIA.

FAN.

1,182,665.

Specification of Letters Patent.

Patented May 9, 1916.

Application filed March 26, 1912. Serial No. 686,439.

To all whom it may concern:

Be it known that we, THOMAS M. EYNON, LEONARD G. PAINE, and EDWARD T. MURPHY, citizens of the United States, and residents of Philadelphia, Pennsylvania, have invented a certain new and useful Fan, of which the following is a specification.

Our invention relates to gas conveying mechanism suitable for forced draft or exhaust and in which the motor is preferably direct-connected to the fan.

The main purpose of our invention is, in a direct connected fan unit, to utilize a part of a hitherto unnecessary difference between 15 inlet and exhaust steam turbine pressures to perform part of the fan duty, improving the efficiency of the unit.

A further purpose of our invention is, in fan blowers, to obtain the same heating of 20 air, per unit of heat in the steam exhausted, for forced draft as in steam jet blowers, and with the same intimate inter-mixture of the moisture from the steam with the air, assisting combustion and preventing clinkering with the cheaper grades of fuel.

A further purpose of our invention is to raise the temperature of the air or gas driven by a motor-fan unit, and to intimately mix the steam with it while its temperature is raised.

A further purpose of our invention is to place the inlet end of a direct-connected fan unit under gas pressure to increase the efficiency of the system.

A further purpose of our invention is to use the exhaust pressure of steam from a turbine to feed any kind of gas, herein, for convenience, referred to as air, to or through a fan driven by the turbine, according to the 35 side of the fan, with respect to the turbine, at which the exhaust is discharged.

A further purpose of our invention is to give direction and force or pressure to inlet air in a direct-connected fan unit by steam 45 entrainment of the air, preferably using steam exhausted from the motor of the unit.

A further purpose of our invention is to interpose a steam jet injector between a steam turbine and a fan operated by it and supply the injector with steam from the 50 exhaust of the turbine.

A further purpose of our invention is to operate a motor and fan as a direct connected unit and to supply the fan with

steam-jet-impelled air blast, preferably between the motor and the fan.

A further purpose of our invention is to supply air to a power-driven fan with considerable velocity and at appreciable pressure, relieving the fan of the work of creating this supply by the vacuum formed and increasing the volume of air handled by the fan at a given speed.

A further purpose of our invention is to reduce the pressure available for the driving of a turbine direct-connected to a fan, suiting the pressure to the economical capacity of the turbine at the desired fan speed and to utilize the difference in pressure for the entrainment of air and intimate 65 intermixture of air with steam, preferably beginning the entrainment and intermixture upon the turbine side of the fan.

A further purpose of our invention is to make a jet blower one stage, preferably the 75 first stage of a double stage "fan."

We have preferred to illustrate our invention by that form thereof which is most practicable, efficient, and inexpensive, and which at the same time well illustrates the 80 principles involved.

Figure 1 is a central longitudinal section of the preferred form of our invention. Fig. 2 is a broken section of a portion of Fig. 1 upon line $x-x$. Fig. 3 is a perspective illustration of the application of our invention to a furnace. Fig. 4 is an elevation partly in section of the fan illustrated. Fig. 5 is a section upon line $y-y$ of Fig. 1 omitting some nozzles. Fig. 6 is a broken section of 90 a modified form.

In the drawings similar numerals of reference indicate like parts.

Direct connected fan units, and particularly turbine-fan units, have been inefficient 95 for several reasons. The permissible speed of the fan is low, because high speed causes excessive noise and wear. This keeps the turbine speed down correspondingly. Lack of room and expense considerations have 100 kept down the diameter of the turbine and prevents the use of expansion turbines. Consequently the speed of the turbine blades has been relatively much too slow for that of the high pressure of the steam supply 105 normally available, with resultant waste of the excess of pressure represented by the unnecessarily high steam pressure. In pre-

vious fan units the union of air and steam has not been so intimate as in steam jet blowers. The air has not been heated as much nor as uniformly per unit of steam introduced; and its power to retain moisture in suspension has been restricted.

We have aimed to obtain the advantage of inlet air heating and thorough steam intermingling with it in this heated condition in 10 a direct connected fan unit, preferably where excess difference of pressure between turbine steam inlet and exhaust is utilized to reduce the work required of the fan.

The wall 1 represents any suitable wall 15 through which air or other gas is to be or may be forced, whether it be considered as inlet or exhaust. The form of wall shown corresponds generally with a furnace wall, such as is used in boiler equipments. In it 20 we have placed a sleeve 2 preferably longitudinally straight in part to conform to the lines of the brick. It may have a facing or flange at 3 to engage with the face of the wall, and is provided with any suitable part 25 as flange 4, for connection, for example, with a mating part 5 upon the shell 6 of a preferably turbine-driven fan. This shell may be flanged at 7 to close the space between the narrower end of the preferably 30 nearly conoidal curved shell and the sleeve 2. For convenience in manufacture we prefer to place most of the flange upon the shell, making the coöperating flange 2', upon the sleeve, small if it be present.

35 While it is evident, and we recognize that, in its broad aspects, our invention is independent of the specific types of fan 8, motor 9 and jet blower 10, we prefer those shown because they coöperate to produce the best 40 service results known to us.

The conoidal form of fan distributes the air blown most uniformly and to the best advantage. We prefer to curve the shell 45 slightly conforming nearly to a general slope or taper nearly parallel to the blades of the fan, and to arrange the jets preferably between parallelism with the axis of the fan on one side and with the intake shell on the other so as to reduce the air friction 50 and cross currents of air as much as possible. The most desirable angle for the location of jets shown is substantially parallel with the blades of the fan. These jets, in turn, co-operate with a steam turbine rather than 55 with another motor because they themselves use steam and are in position conveniently to receive their supply from the turbine exhaust. Moreover, in their inclined position they receive their steam about a relatively 60 large diameter, close to the turbine blades, and discharge it about a relatively small diameter most suitable for the fan supply where the discharge takes place, as preferred, on the turbine side of the fan. We 65 prefer to use a number of jets, circumferen-

tially spaced, rather than a single central jet. By their uniform spacing circumferentially about the axis of the motor and fan they balance the structure mechanically at the same time that they equalize the receipt 70 of the steam and the distribution of the steam and induced air.

Wherever the steam pressure available is much in excess of that desirable for the turbine and must be reduced to avoid excessive 75 speed of the fan, or results in waste of this excess pressure, the back pressure upon the turbine due to the jet blower will not affect the efficiency of the steam turbine. The work required of the fan for a given blast 80 will be greatly reduced and its speed may also be kept low.

We have shown the motor as comprising a casing 11 provided with a steam chest 12, whence the steam is directed through any 85 suitable nozzles 13 against the blades 14 of any type of turbine. Steam is conducted to the turbine through pipe 15. In the form illustrated, the turbine is secured to a hollow shaft 16, supported in bearings 17 and 18, and is prevented from excessive movement in either direction by the cap 19 at one end and the hub 20 of the fan 8 at the other. The hub 20 engages the end 21 of the bearing 18. The interior of the casing 11, as 95 indicated at 22, forms an exhaust chamber for the steam which is used upon the turbine blades and the same exhaust pressure is maintained throughout this compartment, including the portion 23 within which the 100 spokes of the turbine turn. Preferably at a number of points about this exhaust compartment, we provide steam jet nozzles of any suitable form, as at 24, here shown as four in number. We prefer to use a number 105 of nozzles in line for each jet blower, and, hence, cause the jet nozzles 24 to feed steam into the nozzles 25, and these in turn to feed into nozzles 26. Air inlets 27, 28 and 29 are provided between the jets 24 and 25, 110 25 and 26, and between jet 26 and the casing 6, respectively, so that air is entrained by the steam at each point according to the well recognized principles of jet operation.

We have preferred to make use of the 115 conoidal form of fan having blades 30, and to guide and distribute its air influx both by means of the terminal plate 31 and the diagonal placing of the blades, so as to cause it to enter or exhaust to the best advantage through the openings 32 and to be guided by the conformation of the casing at 33.

In all free inlet fans which are used for 120 feed or exhaust purposes, the air upon the inlet or intake side of the fan is in a relatively exhausted condition and its pressure shows a slight vacuum. This is true because the feed of the fan is dependent upon the 125 pressure of the outer air which cannot act un- 130

til the pressure upon the inlet or intake side of the fan has been reduced by the withdrawal of air by the fan blades; and the volumes of the supplies of air to different fans of the same type vary nearly in the same proportion as the degrees of vacuum obtained upon the inlet or intake sides of the fans. The supply of air to the fan is restricted by this vacuum and the fan must do all of the work of creating it and of thus producing a flow or current of air toward the fan. Our invention aims to produce both speed of flow and pressure upon the inlet or intake side of the fan independently of the action of the fan blades and to do this by the operation of differences of pressure which have previously not been wholly utilized in direct-connected turbine-fan units. Even when the motor is not a turbine, the improvement in operation of the fan and reduction of its speed invite the supply of steam jet induction preferably inserted between the motor and the fan, by a separate supply of exhaust, or even live steam, in many installations as seen in Fig. 6, the jets being fed from an annular reservoir 22' similar to that within the casing 11 but independent of the motor 38, whose shaft 16' merely operates through the casing.

30 The turbine casing and jet nozzles are shown as supported from the shell 6 by struts or stiffening strips or ribs 34. The hollow shaft 16, being closed at one end by the cap 19 and at the other end by the plug 35 affords convenient distribution, through any suitably located openings 36, for oil or other lubricant fed thereto by pipe 37.

It will be seen that we apply to the reduction of the work required of the fan a part of the energy of the steam which has been wasted in previous turbine-driven fan constructions because of excessive steam velocity relative to turbine blade speed, and that we secure increased efficiency of the system, and that the jet blower aids or assists the fan and increases its blast whether it discharge between the blower and fan or beyond the fan.

We desire to include as within our invention the various changes and alterations in the structure and arrangement of parts which will naturally occur in the minds of those skilled in the art as a result of our disclosures herein and which come within the range and scope of our claims.

Our process of high pressure steam utilization in turbines direct-connected to fans is advantageous wherever the speed of the effi-

ciency of the turbine is reduced because of relative excessive steam speed.

Having thus described our invention, what we claim as new and desire to secure by Letters Patent is:—

1. In a device of the character stated, in combination, a turbine, a fan turned thereby and a jet blower between the fan and turbine, forcing fluid through the space within which the fan operates.

2. In a device of the character stated, in combination a steam turbine exhausting through a plurality of nozzles, a jet blower construction in line with and including each of said nozzles and a fan aided by the jet blower and driven by the steam turbine.

3. In a device of the character stated, in combination a steam turbine having an exhaust chamber, a jet blowing mechanism connected in advance of said exhaust chamber and at an angle with the axis of the turbine and a fan aided by said jet blowing mechanism.

4. In a device of the character stated, in combination a motor, means for supplying fluid thereto under pressure, a fan driven by the motor, and a plurality of jet blowers directed into the rear of the fan blades, increasing the blast of said fan.

5. In a device of the character stated, in combination a motor, having an exhaust, a steam fed jet blower fed from said exhaust and directed at an angle to the axis of the motor, and a fan driven by the motor receiving the blast from the jet blower on its inlet side and whose blast is thus increased by said jet blower.

6. In a device of the character stated, in combination a steam turbine, a jet blower fed from the exhaust of said turbine and a fan assisted by the jet from said blower.

7. The process of utilization of high steam pressures for direct-connected turbine-fan units which consists in maintaining a considerable back steam pressure upon the exhaust side of the turbine blades to reduce the velocity of the steam affecting the blades, and in utilizing the back pressure in entraining, heating and intermixing air within the steam exhausted by jet discharge of this back pressure steam.
